UNITED STATES PATENT OFFICE.

EMORY I. NICHOLS, OF SAN FRANCISCO, CALIFORNIA.

CHAIR ATTACHMENT.

SPECIFICATION forming part of Letters Patent No. 560,044, dated May 12, 1896.

Application filed December 30, 1895. Serial No. 573,780. (No model.)

To all whom it may concern:

Be it known that I, EMORY I. NICHOLS, a citizen of the United States, residing at San Francisco, in the county of San Francisco and 5 State of California, have invented certain new and useful Improvements in Chair Attachments; and I do declare the following to be a full, clear, and exact description of the invention, such as will enable others skilled in the 10 art to which it appertains to make and use the same, reference being had to the accompanying drawings, and to the letters of reference marked thereon, which form a part of this specification.

15 My invention is an attachment for chairs, and is also intended to be used and operated in other places. It is designed to furnish a moving part carrying and displaying any desired pictures, notices, or advertisements, 20 which are thus better adapted to attract the attention than a stationary picture, notice, or advertisement. These movable pictures, notices, or advertisements are well known, and my purpose is to provide a cheap and effective 25 mechanism and combination by means of which they may be exhibited in hotels, resorts, and other public places.

My invention consists of a chair or an attachment provided with an endless movable 30 part or parts carrying pictures, notices, or advertisements, and with mechanism for moving the said part or parts.

My invention is illustrated in the accompanying drawings, in which—

35 Figure 1 represents a perspective view of a rocking-chair with a portable attachment secured thereto. Figs. 2 and 3 show an edge and front view of a sectional carrier, also the strengthening-pieces on part of the carriers.

40 Fig. 4 shows a modified form of connecting the sections of the carrier. Fig. 5 shows the sections of the carrier secured to the side of a sprocket or driving chain. Fig. 6 represents a vertical section of a rocking-chair, taken 45 from front to rear, showing a recess formed in the back of the chair for the carriers. Fig. 7 shows a front view of the upper part of the back of a chair. Figs. 8 and 9 are front and side views of a portable attachment.

50 Figs. 10 and 11 are front and side views of the top of a portable attachment, showing three open or clear spaces for exposing the

notices. Fig. 12 represents a vertical section of a chair and a side view of a portable attachment. Fig. 13 shows a front view of the 55 operating mechanism with the cover removed. Fig. 14 shows a partial horizontal sectional view of the operating mechanism. Fig. 15 shows a modification of the operating mechanism with the cover removed. Fig. 16 is a 60 modification of the carrier, showing an angular link chain for attaching flexible cards or a continuous flexible sheet.

In the drawings I have shown at A the back of the chair, and in Figs. 1 and 12 I have shown 65 at B an attachment secured to the back A, as in this form the notices, which for convenience I will call "notices," are displayed in the front and rear of the chair. The said attachment B or the back A, as shown in Fig. 70 6, is made sufficiently high to allow the notices to appear above the head of the occupant of the chair in or upon the said attachment or the chair-back. I arrange in the attachment B or in the chair-back A the movable part or 75 parts on which the notices are carried, and for convenience I will call these the "carriers" C. I have shown these carriers in the form of cards or plates loosely joined together, forming an endless chain, band, or web adapted 80 to be moved past an open or clear space on their edges, exposing the notices on their sides, and these carriers may be of any desired shape and of any suitable material, such as cloth, paper, wood, or metal. The upper 85 end of this carrier is supported by the sprocket wheel or roll a, which is journaled in the upper end of the attachment or the chair-back. The lower end of the carrier passes around the driving sprocket wheel or roll b, which is 90 secured to the shaft c of the operating mechanism D, all of which is secured to the end of the attachment B or the chair-back A, the sprocket wheels or rolls a and b, as shown in the drawings, have four sides; but they may have any 95 number of sides or may be round, but I prefer them as shown, as this gives a larger surface of the cards or plates exposed to view.

As shown in Figs. 1, 8, 9, 10, 11, and 12, the chain or carrier is inclosed in an independent 100 casing made of any suitable material. In Fig. 6 I have shown a recess formed in the back of the chair for the reception of the carrier; but it is operated the same as in the inde-

pendent casing. I prefer to make this an independent casing or attachment, so the same may be attached to most any chair now in use, or may be used independent of a chair, 5 if so desired.

The moving of the carrier may be effected by any turning mechanism adapted to bear on the floor, base, or under the chair-seat and to be rendered operative by the rocking, the 10 weight, or other movements of the occupant of the chair or other suitable means for giving the required movement to the carrier for exhibiting the notices, and as a convenient form of such operating mechanism I have 15 shown in the drawings a device for moving the carriers and giving them an intermittent or continuous movement, but I do not confine myself to this. It is easy to devise or adopt some other mechanism for moving the carriers and giving them the required movement, whether directly or indirectly connected therewith.

In Figs. 13 and 14 I have shown an operating device in the form of a casing E with a 20 shaft c journaled therein. On the outer end of this shaft is secured the sprocket or roll b. On the inside of the casing is the disk F, 25 secured to the shaft c. Pivoted on the side of this disk is the pawl e, bearing at its outer 30 end upon the inner periphery of the casing E and against the abutment f, being held to its work by the projection g on its inner end, which travels in the groove h on one side of the disk G. The disk G is loosely journaled 35 on the shaft c and, as shown in Figs. 13 and 14, is rotated by the movement of the arm H. The inner end of this arm is pivoted on the 40 shaft c, and the outer end engages with a pin j, as shown. Secured to the upright rod I in a recess or pocket formed in the arm H is the ball k, that bears against the outer periphery of the smaller diameter of the disk G and the wedge-shaped side of the pocket in the arm H. In a recess or pocket formed in the 45 casing E is the ball l, that bears against the outer periphery of the larger diameter of the disk G and the wedge-shaped side of the pocket. This ball serves as a check as the arm H is making its downward movement. 50 One end of the spring n, as shown by dotted lines in Figs. 13 and 15, is secured to the disk F and the other end is secured to the disk G. The operating-rod I, as shown, has an abutment o. Between this abutment and the casing 55 is the spring K. The reverse action of the rod I is caused by this spring, which holds the rod I to the floor, when used as shown in Figs. 1 and 6, where the pressure comes on the lower end of rod I, but when used as in 60 Fig. 12 or any place where the pressure comes on the upper end of rod I to operate the device the spring K is placed below the abutment o.

In Fig. 15 I have shown a different form of 65 rotating the disk G. In this form I do not use the arm H or the balls k and l, but, as shown, the disk G is rotated by the pawl p,

which is pivoted to the operating-rod I, and is stopped from going backward by the check-pawl r.

Instead of applying the turning mechanism to the shaft and sprocket wheel or roll b, it may be applied directly to the carrier by devices well known for such purposes.

In Figs. 2 and 3 I have shown the cards, 75 plates, or sections of the carrier hinged together, forming an endless chain and overlapping each other similarly to a fan after passing over the sprocket wheels or rolls a and b. This gives a large number of cards or 80 plates for exhibiting notices in a small space, and also when it is desired to change a notice it can be quickly accomplished by removing the card containing such notice and substituting another therefor. I have also shown 85 in Fig. 3, at s, a reinforcement or strengthening-piece secured to or connected with the cards or plates for taking part of the strain of the cards or plates when the cards or plates are made of paper or other light material. 90 This strengthening-piece may be of paper or other light material secured to the side or sides of said cards or plates.

In Figs. 10 and 11 I have shown the upper 95 part of an attachment or chair-back designed to have two carriers, and, as shown, has three open or clear spaces L for exhibiting the notices, but may be operated by one operating mechanism.

In Fig. 12 I have shown a chair with an attachment secured thereto, with the end of the operating-rod I bearing up under the 100 seat of the chair, and is operated by the weight of the occupant of the chair.

I have illustrated in several of the views a 105 convenient arrangement for exposing the notices, as shown at L, which is fixed on the cards or plates of the carrier, and is carried thereon intermittently by the moving mechanism to the apertures L in the attachment or the 110 chair-back, where it is exposed to view for a while and then moved on, and another takes its place. Thus in succession by the movement of the occupant of the chair the whole 115 series, which may cover the surface of the cards or plates of the carrier, is brought into view, every one moving into and out of view, attracting attention by their motion, and exposing several notices in the space necessary for only one.

The intermittent movement of the carrier is accomplished by the operating mechanism, as follows: By the upward and downward movement of the rod I the disk G is rotated a given amount, or until the abutment w in 125 the groove h, as shown by dotted lines on the disk G, comes in contact with the projection g on the inner end of the pawl e. This releases the pawl from its engagement with the abutment f on the inner periphery of the 130 casing E, and the disk F rotates forward until the pawl comes in contact with the next abutment f. This rotates the sprocket or roll b one-fourth of a turn and brings the next no-

tice to view. This forward movement of the disk F is caused by the spring n being secured at one end to the disk G and the other end being secured to the disk F.

5 I have shown the attachment secured to the back of a chair, but it may also be attached to the side of the chair or under the arm or arms of the chair.

I do not confine myself to this form of a 10 carrier, as shown operated in a recess in the back of a chair. The carrier may be made in many different forms and operated on or in a chair-back.

I claim—

15 1. In an attachment for exhibiting pictures, notices, or advertisements, the combination of a casing, suitable pulleys mounted therein, an endless chain of overlapping plates arranged on said pulleys, and means for giving 20 an intermittent movement to the chain.

2. In an attachment for exhibiting pictures, notices, or advertisements, the combination of a casing, suitable pulleys mounted therein, an endless chain of overlapping plates arranged 25 on said pulleys, and means arranged to be engaged with the bottom of a chair for moving the chain by the weight of the occupant of the chair.

3. In an attachment for exhibiting pictures, 30 notices or advertisements, the combination of a chair having a hollow back with one or more exposing-openings, suitable pulleys mounted therein, an endless chain of overlapping plates arranged on said pulleys, and means for 35 moving the chain by the occupant of the chair, substantially as described.

4. In an attachment for exhibiting pictures, notices, or advertisements, the combination of a casing, suitable pulleys mounted therein, 40 an endless chain of overlapping plates with strengthening-pieces secured to their sides and arranged on said pulleys, and means for moving the chain, substantially as and for the purpose described.

45 5. In an attachment for exhibiting pictures, notices, or advertisements, the combination of a casing, suitable pulleys mounted therein,

an endless chain of plates arranged to move around said pulleys, said plates being substantially parallel to the plane of movement 50 of the chain, and means for moving the chain, substantially as and for the purpose described.

6. In an attachment for exhibiting pictures, notices, or advertisements, the combination of 55 a casing, suitable pulleys mounted therein, an endless chain of plates arranged to move around said pulleys, said plates being substantially parallel to the plane of movement 60 of the chain, and means arranged to be engaged with the bottom of a chair for moving the chain, substantially as described.

7. In an attachment for exhibiting pictures, notices or advertisements, the combination of the frame or casing B, the carrier C, the 65 sprocket wheels or rolls a and b, the box or case E, the shaft c, the disk F, with the pawl e, the disk G, the arm H, the balls k and l, the spring n, the rod I, and the spring K, substantially as shown and described. 70

8. In an attachment for chairs for exhibiting pictures, notices or advertisements, the combination with the back A of a chair, the frame or casing B, the carrier C, the sprocket wheels or rolls a and b, the box or case E, the 75 shaft c, the disk F, with the pawl e, the disk G, the spring n, the arm H, the balls k and l, the rod I, and the spring K, substantially as and for the purpose described.

9. In an attachment for exhibiting pictures, 80 notices, or advertisements, the combination of the frame or casing B, the carrier C, the sprockets or rolls a and b, the box or case E, the shaft c, the disk F, with the pawl e, the disk G, the spring n, the pawls r and p, the 85 rod I, and the spring K, substantially as shown and for the purpose described.

In testimony whereof I affix my signature in presence of two witnesses.

EMORY I. NICHOLS.
